CLAIM

The ornamental design for a control panel for elevator, as shown and described.

DESCRIPTION

FIG. 1 is a front, top and right side perspective view of a control panel for elevator, showing an embodiment of our new design;

FIG. 2 is a front elevational view thereof;

FIG. 3 is a rear elevational view thereof;

FIG. 4 is a right side elevational view thereof;

FIG. 5 is a top plan view thereof;

FIG. 6 is a bottom plan view thereof;

FIG. 7 is an enlarged cross-sectional view thereof; taken along line 7-7 of FIG. 2, with the internal system omitted;

FIG. 8 is a reference view showing in use thereof wherein the broken line showing of the environment is for illustrative purposes only and forms no part of the claimed design;

FIG. 9 is an alternate front elevation view of the first embodiment thereof;

FIG. 10 is another alternate front elevation view of the first embodiment thereof;

FIG. 11 is yet another alternate front elevation view of the first embodiment thereof;

FIG. 12 is a front, top and right side perspective view of a control panel for elevator, showing a second embodiment of our new design;

FIG. 13 is a front elevational view thereof;

FIG. 14 is a rear elevational view thereof;

FIG. 15 is a right side elevational view thereof;

FIG. 16 is a top plan view thereof;

FIG. 17 is a bottom plan view thereof;

FIG. 18 is an enlarged cross-sectional view thereof; taken along line 18-18 of FIG. 13, with the internal system omitted;

FIG. 19 is a reference view showing the panel of a second embodiment in use wherein the broken line showing of the environment is for illustrative purposes only and forms no part of the claimed design;

FIG. 20 is another front elevation view of the second embodiment thereof; and,

FIG. 21 is yet another alternate front elevation view of the second embodiment thereof.
